J. Wesley Webber

UNITED STATES PATENT OFFICE.

J. WESLEY WEBBER, OF NEW YORK, N. Y.

IMPROVED KINDLING-WOOD.

Specification forming part of Letters Patent No. 93,775, dated August 17, 1869.

To all whom it may concern:

Be it known that I, J. WESLEY WEBBER, of the city of New York, county of New York, State of New York, have invented a new improvement consisting of accompanying or fastening one or more fire-lighters to each bundle of the common article of manufacture known as "Bundle or Kindling Wood," (see drawing marked C,) having for its object to facilitate the lighting or ignition, by means of the said fire-lighter, of wood, thus saving the consumer the labor of chopping the wood in fine pieces.

The nature of my invention or improvement consists in accompanying or fastening one or more fire-lighters A in a suitable manner, or to the string B of the bundle of the common article of manufacture known as bundle or kindling wood, marked C in the accompanying drawing.

What I claim as my invention, and desire to secure by Letters Patent, is—

The accompanying or fastening one or more fire-lighters, A, to or with the bundle of the common article of manufacture known as bundle or kindling wood, the fire-lighter to be suitably molded or pressed, and to be made of a combustible material, such as rosin or tar, the ingredients of which I do not claim; my invention consisting wholly of accompanying or fastening a fire-lighter, A, to or with the bundle, or at the string B of the bundle of the common article of manufacture known as bundle or kindling wood.

J. WESLEY WEBBER.
